UNITED STATES PATENT OFFICE.

FREDERICK E. HEINIG AND FREDERICK STITZEL, OF LOUISVILLE, KENTUCKY, ASSIGNEES TO THOMAS H. SHERLEY, OF SAME PLACE.

BOTTLE.

SPECIFICATION forming part of Letters Patent No. 293,460, dated February 12, 1884.

Application filed November 30, 1883. (No model.)

To all whom it may concern:

Be it known that we, FREDERICK E. HEINIG and FREDERICK STITZEL, of Louisville, Kentucky, have invented a new and useful 5 Improvement in Bottles, of which the following is a specification.

Our invention relates to bottles, and provides a means by which, when the bottle is once filled—say with whisky, wine, or other 10 matter—and emptied, it cannot be refilled, and the object is to prevent the refilling of the bottle, and thus substituting an article not the product of the manufacturer whose name or brand the bottle may bear; and to this end 15 we contract the neck of the bottle to form, or insert therein a plug containing, a valve-seat, and after the bottle is filled furnish it with a valve, and then fit and fasten into the neck of the bottle, a little above the valve, a plug or 20 stopper, with suitable openings, through which the contents may be poured.

In the accompanying drawings, Figures 1, 2, 3, 5, and 6 are sectional views of a bottle-neck, showing our invention, and different 25 forms in which it may be applied. Fig. 4 shows side views of different forms of the plug or stopper above the valve and different forms of the openings in the plug; and Fig. 7 is a sectional view of an upper plug, a valve, 30 and a lower plug containing a valve-seat.

The same letters indicate the same parts in the different drawings.

A is the neck of a bottle. B is a plug or stopper. C is a valve. D is a cork or other 35 bottle-stopper. E are openings in the plug B. G is a valve-seat.

We prefer to make the upper and lower plugs of glass, and to have the openings which are made in the edge or side of the upper plug 40 of some of the forms shown in the drawings, for the reason that a glass plug can be readily cemented or fastened immovably into the bottle-neck, and the form of openings shown prevent interference with the valve; but we do 45 not wish to be understood as limiting ourselves to the use of that material or the indicated forms of openings.

In Fig. 2 is shown a form of our invention

in which the upper part of the bottle-neck may be made in a separate piece, with the plug B 50 forming a portion of it, and the lower part of the bottle-neck may be contracted to form a valve-seat, and also a seat on which to cement or fasten the detached upper part after the bottle is filled and the valve in place. 55

In practice, with our invention, if the bottle-neck is not contracted so as to form a valve-seat, the bottle is filled, the lower plug, Fig. 7, carrying the valve-seat G, is cemented or fastened into the neck of the bottle A, the 60 valve C, which is formed of glass, hard rubber, or any other suitable material, dropped to its seat G, and the plug B is cemented or fastened into the neck A above the valve C. If the bottle-neck A is contracted so as to form 65 a valve-seat, then, after the bottle has been filled, the valve C is dropped to its seat G in bottle-neck A, and the plug B is then cemented or fastened into the neck A; or, if the form shown in Fig. 2 is used, the detached 70 piece, carrying the plug B, is cemented or fastened onto the neck A. In all cases the plug B is to be placed sufficiently above the valve C to allow the latter a little play, when the bottle is reversed or turned bottom up. 75

The bottle may be stoppered in any of the usual ways.

By means of our invention the contents may be readily poured from the bottle, but the bottle cannot be refilled, and the manufacturer is 80 thus protected from the sale of a spurious article under his name or brand.

Having fully described our invention, what we claim as new, and desire to secure by Letters Patent, is—

In combination with a bottle having an inner projection forming a valve-seat, G, the perforated plug or stopper B, and valve C, secured by a stopper, D, substantially as shown and described.

FREDERICK E. HEINIG.
FREDERICK STITZEL.
